UNITED STATES PATENT OFFICE

JOHN R. SHANNON AND OMER A. ASH, OF DOUGLAS, ARIZONA; SAID ASH ASSIGNOR TO
SAID SHANNON

CARBURETOR

Application filed August 18, 1928. Serial No. 300,486.

This invention relates to carburetors of that character wherein air heated by the exhaust pipe of the engine is drawn over a body of fuel oil or gasoline to become carburetted thereby and is drawn into the engine upon the suction stroke thereof.

The general object of the present invention is to provide a simple, effective and easily applied device of this character which embodies a U-shaped oil containing pipe having means permitting the collection of fuel in the lowest portion of the pipe and to provide means whereby air heated by contact with the exhaust pipe of the engine may be directed into close proximity to this fuel oil to thereby cause the air to become carburetted.

A further object is to provide a device of this character which includes a mixing chamber into which the carburetted air is carried and an intake pipe connected with the intake manifold of the engine and into which the air, after passing through a screen, is carried from the mixing chamber.

Our invention is illustrated in the accompanying drawings wherein—

The figure is a longitudinal sectional diagrammatic view of our improved carburetor.

Referring to these drawings, 10 designates an approximately U-shaped pipe having upwardly extending extremities and a depressed middle portion. This middle portion is depressed below the level of the ends of the pipe to constitute a basin, as it may be termed, designated 11, adapted to hold a certain amount of fuel oil 12. This depressed portion 11 is connected by a pipe 13 to a float valve casing 14 which, in turn is connected by a fitting 15 to a source of supply. The pipe 13 has operating in it the flow controlling valve 16 which may be a needle valve or any other suitable construction, the float maintaining a constant level of oil within the pipe 10.

The pipe 10 at one end is connected to a reversely curved approximately U-shaped hot air pipe 17 which, at its opposite end is adapted to rest upon the exhaust pipe 18 or be disposed in close proximity thereto. The mouth of this pipe 17 is formed with slots 19 permitting of the entrance of air which has been

heated by contact with the exhaust pipe or manifold 18. The pipe 17 is connected to the pipe 10 in any suitable joint or coupling.

The opposite end of pipe 10 from the hot air inlet pipe 17 is enlarged so as to form an approximately globular mixing chamber 20 which is connected by a coupling 21 to an inverted U-shaped pipe 22. A cylindrical screen 23 forms a continuation of the pipe 22 and is disposed within the mixing chamber 20. The pipe 22 is connected by a coupling 24 to an intake pipe 25 or distributor, which at a plurality of points is connected by pipes 26 to the intake manifold 27 of the engine.

These pipes 26 are to be disposed as closely adjacent the intake ports of the several cylinders as possible, and the distributor pipe 25 should be disposed relatively adjacent to the intake manifold.

This carburetor is particularly designed for use with heavy oil and is also particularly adapted for use with motors having four, six, or eight cylinders. The motor will be started with gasoline and as hot air is drawn through the carburetor the gasoline will be shut off and the motor will develop its power from the heavy oil alone. The hot air entering through the hot air pipe 17 vaporizes the oil on the surface of the oil collected in the U-shaped pipe 10. This vapor is lifted into the mixing chamber where the agitation to which the vapor is subjected on a suction stroke, tends to more thoroughly mix the air with the particles of vapor and more thoroughly carbure the air, and as before stated, the distributing pipe 25 is connected as close to the cylinder as possible, even into the intake chamber between the valves in the motor.

This carburetor has been tried out and has proved to be very efficient and operates at relatively low cost. It may be easily applied to any motor and will save fuel and secure more power than with the ordinary carbureting device. The screen 23 prevents a portion of the oil from being carried over into the motor.

This device is to be clamped to the exhaust pipe of the motor and about one tablespoon of oil is maintained in the bottom of the pipe.

10. The air passing over this oil or through the pipe 10 has been highly heated by contact with the exhaust pipe and on the suction stroke the suction tends to draw oil intermingled with the air against the screen 23. 5 The hot air and the vapor from the oil are splashed against this screen and very finely subdivided, atomized and intermingled. The contracted passage between the surface of the oil 12 and the upper wall of the pipe 10 secures such a suction in this part of the pipe 10 as is necessary in order to lift the relatively heavy oil. By forming the device of three approximately U-shaped sections of 15 pipe the device may be readily adjusted to suit different makes of cars and exhaust pipes, and the pipe 17 may be readily rotated in a horizontal plane at right angles to the axis of the inlet mouth of the U-shaped pipe 10 so that this pipe 17 may be adjusted to fit any 20 make or location of exhaust pipe.

What we claim is—

1. A carburetor of the character described including an approximately U-shaped pipe 25 having means for maintaining a depth of fuel oil in the lowest portion of said pipe, a hot air pipe rotatably connected to one leg of the U-shaped pipe and having the form of an inverted U, the outer end of the hot air pipe 30 being adapted to rest upon the exhaust manifold of an engine and take air from the space immediately adjacent the exhaust manifold, the opposite end of the first named pipe being formed with a mixing chamber, a distributor 35 having a plurality of pipe connections adapted to be engaged with the intake manifold of an engine at a plurality of points, and a rotatable pipe connection from the distributor to said mixing chamber.

40. 2. A carburetor of the character described including an approximately U-shaped pipe having means for maintaining a depth of fuel oil in the lowest portion of said pipe, a hot air pipe connected to one leg of the U-shaped 45 pipe and having the form of an inverted U, the outer end of the hot air pipe being adapted to rest upon the exhaust manifold of an engine and take air from the space immediately adjacent the exhaust manifold, the opposite end of the first named pipe being 50 formed with a mixing chamber, a distributor having a plurality of pipe connections adapted to be engaged with the intake manifold of an engine at a plurality of points, a 55 pipe connection from the distributor to said mixing chamber, and a screen forming an extension of the last named pipe and extending into the mixing chamber.

60. 3. A carburetor of the character described including an approximately U-shaped pipe having means for maintaining fuel oil at a predetermined depth in the lowest portion of said pipe, a hot air pipe connected to one leg of the U-shaped pipe and having the form of 65 an inverted U, the outer end of the hot air

70 pipe being adapted to rest upon the exhaust manifold of an engine and take air from the immediate vicinity of the exhaust manifold, the opposite end of the first named pipe being formed with a mixing chamber, a distributor adapted to be engaged with the intake manifold of an engine, an inverted U-shaped pipe connection extending from the distributor to said mixing chamber and having 75 rotatively adjustable connection therewith, and a screen forming an extension of the last named pipe and extending into the mixing chamber.

75 In testimony whereof we hereunto affix our signatures.

JOHN R. SHANNON.
